CIRCUIT-EXTENSION BOX.

1,097,116.

Specification of Letters Patent. Patented May 19, 1914.

Application filed February 8, 1913. Serial No. 747,049.

To all whom it may concern:

Be it known that I, CHAUNCEY W. ABBOTT, residing at Auburn, in the county of Cayuga and State of New York; a citizen of the United States, have invented or discovered certain new and useful Improvements in Circuit-Extension Boxes, of which improvements the following is a specification.

- 10 It is frequently desirable, in buildings wired for electric lighting and like purposes, to change the location of, or to provide new, electrical fixtures. In effecting such alterations the circuits for the re-located or new fixtures are usually picked up at points where the original circuits are readily accessible, as at switches or bracket outlets, and are extended in surface conduits.
- 15 My invention has to do with such extensions of electrical circuits, and the object thereof is to provide an extension box whereby a circuit may be picked up and extended from what is commonly known as a flush switch.

20 In the accompanying drawing, which forms part of my specification, I have illustrated an embodiment of my invention.

Figure 1 is a face view of an extension box the cover being partly broken away in order to show part of the interior construction; Figs. 2 and 3 are sectional views taken on the lines II—II and III—III, respectively, of Fig. 1; and Fig. 4 is a sectional view taken on the line IV—IV, Fig. 2.

25 In the several figures like numerals are used to designate like parts.

Flush switch structures of the character contemplated by my invention are usually of the push-button type, and may be either single or double pole switches depending upon the particular installation, as is well understood.

30 In the illustrative embodiment of my invention a double-pole switch structure is shown, consisting of a rectangular block of insulation 1, having mounted in its opposite ends, two pairs of binding posts 2 and 3 between which electrical continuity may be completed by pivoted conductor arms 4 operated by the push buttons 5. In the original installation of such switches to control electrical currents through inner wall conductors, the usual practice has been and now is to place outlet-boxes 6 in suitably

provided openings in the walls and to extend the electrical conductor conduits into such boxes, as shown in Fig. 2 of the drawings. The flush switch structure, suitably connected to the electrical conductors, is contained within and secured to such outlet box, and a cover, secured to the switch structure, extends over the outer face thereof and beyond the sides and ends of said outlet box, thereby covering whatever irregularities there may be adjacent to the opening in the wall. In order to extend a supplemental circuit from such flush switches and through surface conduits, I provide an extension box adapted to surround, and preferably to sustain, the switch structure, and further so constructed as to form a conductor-carrying passageway around the outer wall of the switch structure, the bottom wall of said passageway forming an outwardly-extending rim or flange adapted to cover the irregularities of the wall adjacent to the opening therein. Such a box may consist of a continuous flat rim or flange 7, a wall portion 8, 9, and a cover 10. The flange 7 is provided with an opening adapted to receive the switch box structure, and is adapted to be secured to the outlet box 6 by means of screws 11. The wall portion has side and end walls 8 resting upon the outer edge of the flange 7, and has an inwardly extending shelf 9 upon which lies the usual attaching strip 12 of the switch structure. Also, the wall portion may be secured to the flange 7 by means of screws 13. The cover 10 fits neatly over the wall portion 8, and, together with the switch structure strip 12, is secured thereto by means of screws 14.

35 As will be readily seen, the box is so constructed as to form a continuous passageway 15 around the switch structure, the bottom of such passageway being formed by the flange 7 which bridges over and hides the irregularities of the wall adjacent to the opening for the outlet box 6.

40 In the practice of my invention any desired arrangement of electrical conductors may be effected. In the installation particularly illustrated herein, the switch structure is effective to control a circuit between the conductors 16 and 17, the conductors 17 leading to a lamp or other fixture. The conductors 16, secured to the same binding posts 3 as are the conductors 16, lead to a newly

installed electrical fixture, and the current passing through the conductors 18 is, of course, independent of the make and break position of the switch. As will be seen, the 5 conductors 18 are carried from one end to the other of the extension box through the passageway 15 and into a surface conduit 19, which is suitably secured to said extension box.

10 In extending a circuit from a switch structure such as I have just described, the original cover is removed, the electrical conductors 16 and 17 released from the binding posts 3 and 2, respectively, and the switch structure removed. The flange 7 is then secured to the box 6 by screws 11 and the walled member 8, 9 to said flange by screws 13. The electrical conductors 16 and 18 may then be secured to the binding posts 3, 15 the conductors 17 to the binding posts 2, and the cover 10 may be attached to the shelf 9 by means of screws 14, extending also through the switch strip 12.

I do not wish to limit myself to the 25 tails of construction herein, for obviously many changes may be made by those skilled in the art without departing from the spirit of my invention.

I claim herein as my invention:

30 1. A two-part circuit extension box comprising a substantially flat bottom portion

adapted to be attached to and to extend laterally from the open side of an outlet box for flush switches, and having a central open area adapted to receive the body of a 35 flush switch, a side wall portion bearing at its lower edge on the outer portion of said bottom and having an inwardly extending rim adapted to have a flush switch secured thereto, and means for connecting said side 40 wall portion to said bottom.

2. The combination with a flush switch structure, and an outlet box having an open side adapted to receive such switch; of a two-part circuit extension box comprising a 45 substantially flat bottom portion secured to the open side of said outlet box and having its outer edges extending beyond the sides of said box, said bottom having a central open area, and a side wall portion bearing at its 50 lower edge on the outer portion of said bottom and having an inwardly extending rim, said switch being secured to said rim and having its body portion extending through the central opening in said bottom and into 55 the outlet box.

In testimony whereof I have hereunto set my hand.

CHAUNCEY W. ABBOTT.
